UNITED STATES PATENT OFFICE.

G. O. WICHERS, OF LAWRENCE, MASSACHUSETTS.

IMPROVED BOX OR CASE FOR OIL-STONES.

Specification forming part of Letters Patent No. 41,561, dated February 9, 1864.

To all whom it may concern:

Be it known that I, G. O. WICHERS, of Lawrence, in the county of Essex and State of Massachusetts, have invented a new and Improved Box or Case for Inclosing Oil-Stones; and I do hereby declare that the following is a full, clear, and exact description of the same, reference being had to the accompanying drawings, making a part of this specification, in which—

Figure 1 is a longitudinal vertical section of my invention taken in the line $x x$, Fig. 2; Fig. 2, a plan or top view of the same, partly in section.

Similar letters of reference indicate corresponding parts in the two figures.

Oil-stones have hitherto been fitted in wooden blocks and provided with a wooden cover to protect them from dust and preserve them from breakage. The stones have either been fitted permanently in the blocks or adjusted snugly within them, so as to be in contact with the wood. This mode of boxing or incasing oil-stones is attended with the following disadvantages: First, the wood absorbs the oil which escapes from the stone, and soon becomes completely saturated with it, so that it cannot be handled without soiling the fingers; second, the stone being either permanently fitted in the block or adjusted snugly within it, cannot be readily removed and turned so as to have a fresh side placed uppermost.

My invention is designed to obviate these difficulties; and it consists in having a box composed of cast metal and of two equal longitudinal parts, one of which is provided internally with projections and a set-screw for the proper adjustment of the stone within it, and the other serving as a cover, the latter as well as the part first mentioned being provided with knife-edge projections to prevent them from slipping when in use, as hereinafter fully set forth.

To enable those skilled in the art to fully understand and construct my invention, I will proceed to describe it.

A represents the lower, and B the upper, part of a quadrilateral cast-metal box of any suitable or desired dimensions. The lower part, A, of the box has upright projections a on its bottom for the stone to rest upon, and

it has projections b at the inner side of one end to serve as bearings for one end of the stone, the opposite end of the part A having a set-screw, C, passing horizontally through it and bearing against the opposite end of the stone.

The stone, designated by D, is somewhat smaller than the interior of the part A of the box, so that a space will be allowed between the sides of the latter, the projections a admitting of a space being allowed underneath the stone, and the projections b effecting the same object at one end of it, while the dimensions of the stone admit of a space being at its opposite end, against which the set-screw C bears. (See Fig. 1.)

The stone D, it will be seen, is retained firmly in the part A of the box by screwing up the set-screw C, and the stone may, by loosening or unscrewing the set-screw C, be readily lifted out of A and turned either side uppermost, and again secured in A. Thus, when one side of a stone becomes worn unevenly by use, a fresh plane surface by the turning of the stone may be readily adjusted in position for use.

The upper part, B, of the box is the cover, which simply rests on the top of A, and is retained in position by a pendent knife-edged projection, c , at each end, said projections extending the whole width of the cover, and when B is placed on A fitting within the upper parts of the ends of the latter, as shown in Fig. 1. The lower part, A, is provided with similar projections, d , at its ends. The projections d prevent the part A from slipping on the surface on which it rests when the stone is used. The projections c of the part or cover B perform a similar office for the latter, which has a strap, E, cemented or otherwise secured to its upper surface for putting a fine edge on the tool after it has been sharpened on the stone.

From the above description it will be seen that the oil which drips from the stone will pass down within the part A, instead of running down on the outer side of it, and said part as well as the stone may be cleaned with the greatest facility by simply removing the stone from A. Thus the stone and box may with but little trouble always be kept clean and in a proper condition for use.

The parts A and B are designed to be of equal dimensions, and stones of square form in their transverse section would be preferable, to admit of any one of their sides being adjusted uppermost.

Having thus described my invention, what I claim as new, and desire to secure by Letters Patent, is—

1. A box or case for oil-stones, composed of two cast-metal parts, A B, one of which, A, is provided internally with projections *a b* and a set-screw, C, or its equivalent, for holding

the stone in position and admitting of an oil-passage all around it, and the other, B, made to serve as a cover, substantially as set forth.

2. The knife-edged projections *d e*, when used in combination with and formed on or cast with the parts A B, for the purpose specified.

G. O. WICHERS.
